UNITED STATES PATENT OFFICE.

EMANUEL HENRIKSON, OF WETHERSFIELD, CONNECTICUT, ASSIGNOR TO PRATT & WHITNEY COMPANY, OF HARTFORD, CONNECTICUT, A CORPORATION OF NEW JERSEY.

SLIDE-ADJUSTING MECHANISM FOR TURRET-LATHES.

1,233,665.

Specification of Letters Patent. Patented July 17, 1917.

Application filed October 9, 1916. Serial No. 124,495.

To all whom it may concern:

Be it known that I, EMANUEL HENRIKSON, a citizen of the United States, residing at Wethersfield, in the county of Hartford, 5 and State of Connecticut, have invented certain new and useful Improvements in Slide-Adjusting Mechanism for Turret-Lathes, of which the following is a specification.

This invention relates to slide adjusting mechanism for turret lathes, the primary object of the invention being to provide means of an effective nature of compact construction.

In the drawings accompanying and forming part of the present specification I have shown in detail one convenient form of embodiment of the invention, which to enable those skilled in the art to practise the same will be set forth fully in the following description. I do not restrict myself to this particular disclosure; I may depart therefrom in several respects within the scope of the invention defined by the claims following said description.

Referring to said drawings:

Figure 1 is a front elevation of a turret lathe involving the invention.

Fig. 2 is a vertical sectional view of the turret, its slide and certain accessories hereinafter more particularly described and on a larger scale.

Like characters refer to like parts in both views.

In Fig. 1 the numeral 2 denotes the base or bed, and 3 the upright or standard rising therefrom of a vertical turret lathe. The column or upright is provided with ways for supporting a slide as 4 for vertical adjustment. On the front of the slide is a hollow stem or stud 5, constituting a suitable pivot for the turret 6 one of the elements of the slide-adjusting means for compactness extending through the pivot of the turret. Extending through said pivot 5 are concentric 45 hollow shafts or tubes as 7, 8 and 9. The tube 7 is connected at its front end as by keying with the disk 10 and at its rear has pinned thereto a worm gear 11. This disk 10 is pinned or otherwise suitably connected 50 with the turret. They form part of the indexing mechanism to which I have alluded and therefore form no part of the present invention. The intermediate and longer hollow shaft 8 constitutes part of the means by 55 which the indexing mechanism can be thrown

into action and also as may be inferred constitutes no part of the invention, which relates as noted merely to the adjusting mechanism; that is the means for changing the position of the slide 4 on its support as 3. 60

The shaft 9 which is longer than the two other hollow shafts 7 and 8 is provided with suitable means as the hand wheel 12 by which the same may be turned. As illustrated said hand wheel is connected as by 65 keying with the front end of said shaft. The means shown for effecting the movement of the slide vertically involves a bevel gear as 14 shown as keyed at 15 to the rear end of said shaft 9, the hub of said bevel gear 70 being supported for rotation in a bushing as 16 which supports the outer ends of the two inner shafts 8 and 9. Although the slide 4 supports the outermost shaft 7, it does not project into the bushing 16. This, however, 75 is a detail. In mesh with the bevel gear 14 is a practically duplicate bevel gear 17 having an elongated upstanding hub 18 fitting freely in the socket 19 in the lower end of the bearing internally threaded sleeve 20 disposed in the overhanging extension 21 of the slide 4. In the present case this bearing sleeve is held against rotation and the pins 22 fitting complementary seats in the sleeve 80 and extension 21 may be provided to insure 85 the relation. Extending through said bearing sleeve 20 is a screw rod or shaft 23. This screw rod or shaft also extends through the bevel gear 17 and has a rotative connection therewith, for instance by the key 24. The upper end of said screw shaft has a swivel connection with a bracket as 25 connected with the overhanging part of the upright or column 3 as shown in Fig. 1.

It will be clear that owing to the described 95 construction, when the hand wheel 12 is turned, the slide 4 through the intermediate parts will be raised or lowered, its particular movement depending upon the direction in which the hand wheel is turned. The elongated bearing sleeve 20 is not only non-rotative, but it is immovable. Owing to its threaded connection with the screw shaft 23, said bearing sleeve acts as a fixed feed nut to effect the raising or lowering of the 100 slide when the screw rod or shaft 23 is turned through the primary effect of the hand wheel 12 in the manner set forth.

It is unnecessary for me to describe the 105 turret locking mechanism of which the bolts 110

30 form a part. This locking mechanism is not of my sole invention. It is covered in an application filed jointly by me and Arthur L. Frederickson, filed October 12, 1916, Serial No. 125,308 and to which by permission I refer.

What I claim is:

- 10 1. The combination of a slide, a turret pivotally mounted on said slide, a shaft extending through the pivot of the turret and supported by the slide, and means actuated by said shaft for effecting the adjustment of the slide on its support.
- 15 2. The combination of a slide and a turret pivotally mounted thereon, a shaft extending through the pivot of the turret and supported by the slide, a nut and a feed screw in co-operative relation with the slide, and means actuated by said shaft for effecting a relative motion of the nut and the feed screw to adjust the slide on its support.
- 20 3. The combination of a slide and a turret pivotally mounted thereon, a non-rotative nut fixed to the slide, a rotary screw extending through the nut and immovable in the direction of its length, a shaft extending through the pivot of the turret, and means
- 25

actuated by said shaft for turning the feed screw.

4. The combination of a slide and a turret 30 pivotally mounted thereon, a feed screw immovable in the direction of its length and having a swivel connection with the framing, a nut having a fixed connection with the slide and receiving said feed screw for rotation, a shaft extending through the pivot of the turret, and means actuated by the shaft for rotating the feed screw.

5. The combination of a slide and a turret pivotally mounted thereon, a rotary shaft 40 extending through said turret and having a bevel gear fixed thereto, a nut fixed on the slide, a rotary feed screw immovable in the direction of its length and extending through the nut, and a second bevel gear rotative in 45 the nut, having a rotative connection with the feed screw and in mesh with the other bevel gear.

In testimony whereof I affix my signature in the presence of two witnesses.

EMANUEL HENRIKSON.

Witnesses:

JOSEPH E. COOLEY,
HEATH SUTHERLAND.
